AUTOMATIC DOUBLE WALL CARTON

Hubert V. Bolding, Jeffersonville, Ind., assignor to The Bradley & Gilbert Company, Louisville, Ky., a corporation of Kentucky

Application January 24, 1955, Serial No. 483,680

3 Claims. (Cl. 229—41)

This invention relates to a collapsible, single-blank, double wall carton which may be completely manufactured by automatic machinery, and then shipped to a user in collapsed condition. The collapsed carton may then be placed in an automatic loading machine and erected by merely pushing the outer flattened corners of the carton. No other operations are required by the user to place the carton in condition for use.

When the carton is in collapsed condition, the bottom members are in face-to-face engagement with each other. Upon erection, the bottom members are automatically moved to their bottom forming positions and during this movement the inner walls will be moved by the bottom members from face-to-face engagement with the outer walls into spaced relation thereto.

Preferably one of the bottom members is dimensioned to provide an upper smooth cover ply for the bottom, its configuration being the same as the area defined by the inner walls, when erected. In a carton of this smooth bottom type, it is preferred that the bottom members be sandwiched between the inner and outer walls when the carton is in collapsed condition. Upon erection the bottom members will be automatically drawn down to their bottom forming positions and during this movement the inner walls will be drawn downwardly by the bottom members from face-to-face engagement with the outer walls into spaced relation therewith.

To provide rigidity to the erected carton, a bracing structural relationship is provided at the adjacent edges of the inner walls. Further, the smooth upper surface bottom member is equipped with locking tab means which automatically coat with suitable slots in an inner wall upon erection to maintain the carton in erected condition.

Attempts to meet the needs of the industry in this field are exemplified by the patent to Arneson, No. 2,349,241, and the patent to Freel et al., No. 2,581,400. This invention, as will be further explained hereinafter, presents a new concept in box design which enables the production of a collapsible carton of a certain structural type which can be completely assembled by the carton manufacturer, shipped in collapsed condition, and erected by machinery exerting minimum forces on opposite collapsed corners of the carton. Shipping costs are reduced, erection costs are minimized, and shut-down losses of the carton loading machine due to erection failures are drastically reduced.

Various other objects and meritorious features of the invention will be apparent from the following description taken in conjunction with the drawings wherein like numerals refer to like parts throughout the figures and wherein:

Fig. 1 is a plan view of a single integral blank from which a carton of the instant invention may be formed;

Fig. 2 is a perspective view looking at the upper portion of the carton in erected condition;

Fig. 3 is a perspective view looking at the upper portion of the carton in collapsed condition;

2

Fig. 4 is a sectional side view taken on line 4—4 of Fig. 2;

Fig. 5 is a sectional top view taken on line 5—5 of Fig. 2;

Fig. 6 is a perspective view looking at the bottom portion of the carton in partially erected condition;

Fig. 7 is a perspective view looking at the bottom portion of the carton in erected condition;

Fig. 8 is a plan view of the end portion of a single integral blank on reduced scale designed to provide a covered box; and

Fig. 9 is a sectional side view of the end portion of the blank shown in Fig. 8, this view showing this portion of the blank in erected condition.

Referring now to Fig. 1, it will be seen that the single blank is cut and scored to form four outer walls 15, 16, 17 and 18, an end attaching member 19 being provided on wall 18 to enable fixed connection of wall 18 to wall 15. Cross hatching on member 19 as well as elsewhere on the blank is intended to indicate glue areas.

Top frame panels 20, 21, 22 and 23 are integrally hinged by their respective score lines 24, 25, 26 and 27 to the top edges of their respective outer walls 15 to 18. Similarly, inner walls 28, 29, 30 and 31 are integrally hinged by their respective score lines 32, 33, 34 and 35 to their respective top frame panels 20 to 23.

Bottom anchor panels 36, 37, 38 and 39 are integrally hinged by their respective score lines 40, 41, 42 and 43 to their respective inner walls 28 to 31.

At the bottom edges of the outer walls 15 to 18 are integrally hinged bottom members 44, 45, 46 and 47 by their respective score lines 48, 49, 50 and 51. Glue areas 52, 53, 54 and 55 fixedly secure the bottom anchor panels 36 to 39 to their respective bottom members 44 to 47.

Bottom folding tabs 56 and 57 are integrally hinged to the bottom members 44 and 46 by diagonal score lines 58 and 59, respectively. Cross hatching on the bottom folding tabs 56 and 57 indicates glue areas which fixedly secure the tab 56 to the adjacent bottom member 45 and the tab 57 to the adjacent bottom member 47.

The edges of top frame panels 21 and 23 are diagonally cut to facilitate assembly and the edges of top frame panels 20 and 22 are convexly cut to cover the edges of top frame panels 21 and 23 and present a tailored appearance as shown in Fig. 2. The corner edges of the inner walls 28 to 31 adjacent the top frame panels 21 to 23 are also diagonally cut to facilitate assembly.

It will be noted that the adjacent edges of the inner walls 28 to 31 are slightly spaced from each other and that the bottom anchor panels 36 to 39 are shorter than their respective score lines 48 to 51 adjacent to which they are glued; this facilitates assembly also.

The inner walls 28 and 30 have score lines 60—61 and 62—63, respectively, which are preferably cut-score lines to provide minimum resistance to swinging movement of the edge spacer panels 64—65 and 66—67.

The inner walls 29 and 31 have cam edges 68—69 and 70—71, respectively, which engage their respective edge spacer panels 64—65 and 66—67 to swing them outwardly as seen in Fig. 5 when the carton is erected.

The bottom members 44 and 46 are triangular in configuration and the bottom members 45 and 47 have diagonally cut edges extending from their respective score lines 49 and 51 which form trapezoidal portions from which extend rectangular portions 72 and 73. The longer rectangular portion 72 is dimensioned to provide an upper smooth cover ply for the bottom which completely fills the rectangular space between the inner walls 28 to 31 when the carton is in erected condition. The rectangular portion 73 is cut shorter than rectangular portion 72 to facilitate erection of the carton.

Locking tabs 75 extend from the rectangular portion 72 of bottom member 45 and upon erection of the carton, these tabs 75 move downwardly past the face of inner wall 31 and into the slots 76 formed by the completely severed portions 77 of score line 43, as shown in Figs. 4 and 5.

Referring now to Figs. 2 and 3, it will be seen that the collapsed carton of Fig. 3 may be erected from a substantially collapsed parallelogram configuration to the rectangular configuration of Fig. 2 by merely applying pressure in the direction of arrows 80 and 81 on a first pair of diagonally opposite corners 78 and 79. The erected carton will be rigidly locked in position by the engagement of locking tabs 76 in slots 77. Collapsing of the carton may be readily accomplished by applying pressure on the other or second pair of diagonally opposite corners 82 and 83.

When erecting pressure is applied to the first pair of corners 78 and 79, bottom folding tab 57, which is fixedly connected to bottom member 47 and integrally hinged to bottom member 46 by a score line 59, causes downward hinged movement of the bottom members 46 and 47 from their vertical collapsed condition within the collapsed outer walls 15 to 18 of Fig. 3 to a horizontal condition at the bottom of the erected outer walls as seen in Fig. 2. Similarly, the bottom folding tab 56 causes downward hinged movement of the bottom members 44 and 45.

The score line 59, to which bottom folding tab 57 is integrally hinged, extends diagonally upwardly from the bottom of corner 79 and toward corner 78 when the carton is collapsed. Similarly, the score line 58, to which bottom folding tab 56 is integrally hinged, extends diagonally upwardly from the bottom of corner 78 toward corner 79 when the carton is collapsed. This arrangement will be apparent from Fig. 6 wherein the carton is shown in partially erected condition and the score lines 58 and 59 are moving toward their horizontal position as shown in Fig. 7.

The bottom folding tab 57 in effect forms an L-shaped bottom forming unit of bottom members 46 and 47 which is moved as a single unit during erection of the box. Likewise, the tab 56 joins bottom members 44 and 45 into a single L-shaped bottom forming unit.

As the tab 56 pivotally moves bottom members 44 and 45 to a horizontal bottom forming position, the anchor panels 36 and 37 which are fixedly secured to bottom members 44 and 45, respectively, are carried in an arcuate path from a vertical position to a horizontal position, causing the inner walls 28 and 29 to be spaced from their respective outer walls 15 and 16 and drawing top frame panels 20 and 21 downwardly from their upwardly extending position of Fig. 3 to their horizontal position of Figs. 2 and 4.

As the inner walls 28 to 31 are pulled downwardly and moved horizontally with respect to each other during erection of the carton, the cam edges 68 to 71 engage their respective edge spacer panels 64 to 67 and force them outwardly to a position at right angles to their respective inner walls 28 and 30. The top sectional view of Fig. 5 shows edge spacer panels 66 and 67 in final erected position in face-to-face engagement with the inner walls 29 and 31, respectively. The cam edges 69 and 70 extend toward and aid in bracing outer wall 17. Similarly, edge spacer panels 64 and 65 are in face-to-face contact with inner walls 31 and 29, respectively, and the cam edges 68 and 71 extend toward outer wall 15.

Various modifications of this invention may be made to adapt the carton for holding various products in different fashions. In Figs. 8 and 9 is shown in reduced scale a modification of the blank which enables the provision of an integrally hinged cover from a single blank of material. The same numerals as applied to the blank of Fig. 1 are applied in Fig. 8 where possible. An outer wall 96 is integrally hinged to outer wall 17 as in Fig. 1.

A cover 90 with locking extensions 91, which mate with slots (not shown) at the upper edge of wall 16, is integrally hinged to the top edge of the outer wall 96 on hinge line 92. To the lower edge of outer wall 96 is integrally hinged a bottom member 93, a return bottom flap 94, an inner wall 95, a top frame panel 97 and a glue panel 98. The cross hatched areas indicate glue areas. Referring now to Fig. 9, it will be seen that the collapsible and double wall features are retained with the covered box design. Instead of the single thickness bottom member 47 of Fig. 1, the covered box has a two-ply bottom member made up of member 93 glued to return flap 94.

Various modifications of this invention will be apparent to those skilled in the art and for that reason I wish to limit myself only within the scope of the appended claims.

I claim:

1. In a single-blank collapsible carton, the combination of four outer walls hinged together and forming a continuous and collapsible outer wall structure, opposed outer walls being of equal length, each of said outer walls having a top edge and a bottom edge, four top frame panels, each of said top frame panels being integrally hinged to the top edge of one of said outer walls and extending inwardly thereof, four inner walls, each of said inner walls being integrally hinged to one of said top frame panels and extending in parallel spaced relation to its respective outer wall when in erected condition, four bottom anchor panels, each of said bottom anchor panels being integrally hinged to one of said inner walls, four bottom members, each of said bottom members being integrally hinged to the bottom edge of one of said outer walls, said bottom anchor panels being fixedly secured to their respective bottom members, a first opposed pair of said bottom members having diagonal edges at diagonally opposite positions, and two bottom folding tabs, each of said bottom folding tabs being integrally hinged to one of said diagonal edges and fixedly secured to that one of the remaining opposed pair of said bottom members lying respectively adjacent thereto, a first pair of opposed inner walls having edge spacer panels integrally hinged at their vertical edges, and the remaining pair of inner walls having cam edges at their vertical edges for swinging said edge spacer panels outwardly toward and into engagement with their respective outer walls and for maintaining the vertical edges of said spacer panels in rigidifying abutting engagement with their respective outer walls.
2. In a single-blank collapsible carton, the combination of four vertical outer walls hinged together and forming a continuous, rectangular and collapsible outer wall structure, said outer walls including three outer walls and a cover-hinging outer wall, each of said three outer walls having a top edge and a bottom edge, three horizontal top frame panels, each of said frame panels being integrally hinged to the top edge of one of three said outer walls and extending inwardly thereof, three inner walls, each of said inner walls being integrally hinged to one of said three top frame panels and depending in parallelism with its respective outer wall, three bottom anchor panels, each of said anchor panels being integrally hinged to one of said three inner walls, four bottom members, each of said bottom members being integrally hinged to the bottom edge of one of said outer walls, said three bottom anchor panels being fixedly secured to their respective bottom members the bottom member integrally hinged to the bottom edge of said cover-hinging outer wall having an extension including a fourth bottom wall anchor panel integrally hinged at one edge to the edge of said bottom wall opposite said bottom edge and affixed in face-to-face relation with the upper surface thereof, a fourth inner wall integrally hinged to the opposite edge of said fourth anchor panel and extending in parallelism with its respective outer wall, a fourth horizontal top frame panel integrally hinged to the

5. In a single-blank collapsible carton, the combination of four vertical outer walls hinged together and forming a continuous, rectangular and collapsible outer wall structure, said outer walls including three outer walls and a cover-hinging outer wall, each of said three outer walls having a top edge and a bottom edge, three horizontal top frame panels, each of said frame panels being integrally hinged to the top edge of one of three said outer walls and extending inwardly thereof, three inner walls, each of said inner walls being integrally hinged to one of said three top frame panels and depending in parallelism with its respective outer wall, three bottom anchor panels, each of said anchor panels being integrally hinged to one of said three inner walls, four bottom members, each of said bottom members being integrally hinged to the bottom edge of one of said outer walls, said three bottom anchor panels being fixedly secured to their respective bottom members the bottom member integrally hinged to the bottom edge of said cover-hinging outer wall having an extension including a fourth bottom wall anchor panel integrally hinged at one edge to the edge of said bottom wall opposite said bottom edge and affixed in face-to-face relation with the upper surface thereof, a fourth inner wall integrally hinged to the opposite edge of said fourth anchor panel and extending in parallelism with its respective outer wall, a fourth horizontal top frame panel integrally hinged to the

top edge of said fourth inner wall, and a glue panel integrally hinged to said fourth frame panel and affixed to the inner upper surface of said cover-hinging outer wall, and a cover integrally hinged to the top edge of said cover-hinging outer wall, a first opposed pair of said bottom members having diagonal edges extending diagonally inwardly from a first pair of diagonally opposite corners of the carton, and two actuating tabs, each of said actuating tabs being integrally hinged to one of said diagonal edges and fixedly secured to the adjacent one of the remaining opposed pair of said bottom members whereby upon collapsing the carton into substantially a collapsed parallelogram configuration, the bottom panels are moved upwardly within the carton and the actuating tabs are sandwiched between their respective adjacent bottom panels, a first pair of opposed inner walls having edge spacer panels integrally hinged at their vertical edges, and the remaining pair of inner walls having cam edges at their vertical edges for swinging said edge spacer panels outwardly toward and into engagement with their respective outer walls and for maintaining the vertical edges of said spacer panels in rigidifying abutting engagement with their respective outer walls.

3. In a single blank, collapsible carton, the combination of four vertical outer walls hinged together and forming a continuous rectangular and collapsible outer wall structure, each of said outer walls having a top edge and a bottom edge, four horizontal top frame panels, each of said frame panels being integrally hinged to the top edge of one of said outer walls and extending inwardly thereof, four inner walls, each of said inner walls being integrally hinged to one of said top frame panels and depending in parallelism with its respective outer wall, four bottom anchor panels, each of said anchor panels being integrally hinged to one of said
